(57) CLAIM

The ornamental design for a USB set-up key, as shown and described.

DESCRIPTION

FIG. 1 is a top perspective view of a USB set-up key showing our new design;

FIG. 2 is a bottom perspective view thereof;

FIG. 3 is a top view thereof;

FIG. 4 is a bottom view thereof;

FIG. 5 is a side view thereof;

FIG. 6 is another side view thereof;

FIG. 7 is an end view thereof; and,

FIG. 8 is another end view thereof.

In the drawings, the broken lines depict environmental subject matter only and form no part of the claimed design.
